UNITED STATES PATENT OFFICE.

EDWARD J. VON PEIN, OF DAYTON, OHIO, ASSIGNOR, BY MESNE ASSIGNMENTS, TO THE NATIONAL CASH REGISTER COMPANY, OF DAYTON, OHIO, A CORPORATION OF MARYLAND.

CASH REGISTER.

Application filed April 4, 1921. Serial No. 458,510.

This invention relates to improvements in accounting machines and has more particular relation to those which, in addition to making a record upon a totalizer, make an additional printed record of all transactions, and indicate the same, and in particular accumulate totals and print them.

It is an object of this invention to provide mechanism whereby an itemized receipt with total may be issued by a few, simple, conveniently performed manipulations.

Another object is the provision of mechanism for speeding up the operation of the machine to reduce the time consumed in issuing such receipt.

With these and incidental objects in view, the invention consists of certain novel feature of construction and combinations of parts, the essential elements of which are set forth in appended claims, and a preferred form of embodiment of which is hereinafter described with reference to the drawings which accompany and form part of the specification.

Of said drawings:

Fig. 1 is a vertical transverse sectional view of the machine, taken on the line 1—1 of Fig. 3.

Fig. 2 is a vertical sectional view of the recording totalizer.

Fig. 3 is a top plan view of a portion of the machine showing the recording totalizer and printing mechanism.

Fig. 4 is a side elevation of the mechanism for rotating the operating shaft.

Fig. 5 is a vertical transverse sectional view of the printer, taken on the line 5—5 of Fig. 3.

Fig. 6 is an elevation of the right hand end of the machine, showing the electric motor and a portion of the printer.

Fig. 7 shows an itemized receipt issued by the machine.

Fig. 8 shows a portion of the record strip.

Fig. 9 is a top plan view of the electric motor starting key mechanism.

Fig. 10 is a plan view of the electric motor switch mechanism.

Fig. 11 is a detail sectional view of the electric motor switch mechanism taken on the line 11—11 of Fig. 10.

Fig. 12 is a rear elevation of the electric motor and driving mechanism. 55

Fig. 13 is a detail sectional view of a portion of the motor key mechanism, taken on the line 13—13 of Fig. 14.

Fig. 14 is a side elevational view of the electric motor starting key mechanism. 60

Fig. 15 is a rear elevation of the motor driving mechanism shown partly in section.

Fig. 16 is a vertical transverse section taken on the line 16—16 of Fig. 15.

Fig. 17 is a vertical transverse section 65 taken on the line 17—17 of Fig. 15.

Fig. 18 is a vertical transverse section taken on the line 18—18 of Fig. 15.

Fig. 19 is a detail view of part of the totalizer resetting mechanism. 70

The objects of the invention are herein shown as carried out in connection with a machine of the general type shown in Letters Patent of the United States to Cleal, 718,565 and 773,060, and to Von Pein, No. 75 1,555,534, Sept. 29, 1925, and in applications for Letters Patent of the United States of Edward J. Von Pein, Serial Nos. 293,141 and 376,088, filed April 28, 1919, and April 23, 1920, respectively. 80

This machine comprises a series of manipulative devices, such as keys, which operate mechanism for indicating items, entering the items in one or more totalizers, and setting up type and operating a printing mechanism to make a printed record of items on a receipt which is subsequently issued by the machine. The machine also includes mechanism for printing the amount accumulated in a totalizer on a record strip 85 kept in the machine and on said receipt. 90

Keys 30 (Figs. 1 and 3) are pivoted upon a transverse rod 31, and when the forward ends of one or more of them are depressed they engage and rock a key coupler 32 having trunnions 33 seated in bearings in the side frames 34. Pivotaly attached to the rear end of each key 30 is an upright member 35, each formed with a shouldered slot 36, adapted, when a key 30 is operated, to engage a transverse rod 37 on a frame 38, pivoted on a transverse rod 39, to rock said frame different distances according to the value represented by the operated key. The slots 36 are located at varying distances 100 from the pivotal connection between the up-

rights and keys, to effect a differential rocking of the frames 38. There is a frame 38 for each denominational group of keys 30 but only one is here disclosed in full. Each frame has attached to it a registering segment 40 (Fig. 1).

At each operation of the keys 30 (Fig. 4), which imparts an oscillatory motion to the key coupler 32, an upright member 77 is 10 raised and lowered to give a complete revolution to a shaft 78. The key coupler 32 is connected to the upright member 77 by a roller 79 cooperating with a slot 80 formed in the upright member 77, which is provided 15 with a bifurcated end guided on a stud 88 and with two opposing racks adapted alternately to mesh with a pinion 83 fast on the shaft 78. A spring 86 holds the left hand rack in engagement with the pinion 78 which 20 relation of rack and pinion is maintained during the upward movement of the member 77 by means of a flange 84 on said member and a cooperating member 85 projecting from the frame of the machine. At the end 25 of its upward movement the member 77 is forced to the left and the right hand rack moved into engagement with the pinion, the flanges 84 and 85 cooperating to maintain this relation during the downward 30 movement of said member 77. A ratchet wheel 81 on the shaft 78 and a pawl 82 pivoted on the frame prevent retrograde motion of the shaft 78 after a key 30 has been depressed a predetermined amount. A cam 35 791 (Fig. 1) carried by the shaft 78 cooperates with rollers 811 on a bifurcated arm 801 secured to the totalizer frame 41 to rock the pinions of the rotatable elements of the totalizer into engagement with the 40 actuating segments. All of this mechanism is well known in the art and is shown here for illustrative purposes only.

The totalizers are of the usual form, but only the right hand or transaction and printing totalizer is here shown. It is mounted on a pivoted frame 41, and comprises a plurality of rotatable elements, each appropriate to a numerical order, as is usual in these devices. Each of the rotatable elements includes a gear 42 in mesh with a gear 43 rotatably mounted on a shaft 44 mounted in brackets on the totalizer frame 41 and carrying a stepped scroll 45. The lower order of rotatable elements also includes 50 pinions adapted to engage the registering segments as the totalizer is rocked. Any movement of the totalizer elements will be transmitted directly to the stepped scrolls 45, so that said scrolls are caused to rotate 55 to a position appropriate to the total of the items entered on the totalizer.

Each of the segments 40 (Figs. 1 and 3) for the right hand or recording totalizer, also meshes with a pinion 49. One of these pinions is fast to the left hand end of a

shaft 50 while the other pinions are mounted upon the left hand ends of telescopic sleeves 51 (Figs. 1 and 5) which extend to the right beyond the frame of the machine proper and on their right hand ends carry printing wheels 52 for printing the detail transactions on a receipt strip 53. This strip (Figs. 6 and 7) is run from a supply roll (not shown) around a guide roll 55, to a severing plate 57, passing between the type carriers 52 and a platen 58 so that when the platen is operated, an impression will be made on the strip.

The mechanism for feeding the issuing receipt strip 53 comprises a feed roller 65 80 (Fig. 6) mounted on a shaft 66, journaled in the printer plate 67 and having fast thereto a ratchet wheel (not shown) which is engaged by a spring controlled pawl 68 pivoted on an arm 69 loose on an extension of the oscillatory stud 33 upon which the key coupler oscillates. Fast on this extension and just inside of the plate 67 is an arm 260 which carries a pin 261 extending through a slot 262 in said plate and into a hole drilled in the arm 69. At each operation of the key 30, which imparts an oscillatory motion to the key coupler 32, the pawl 68 through arm 260, pin 261 and arm 69 will cause the feed roller 65 to rotate in a counter clockwise direction. A spring controlled retaining pawl 70 prevents retrograde motion of the roller 65. Directly above the feed roller 65 and in contact with the same is a tension roller 71 freely mounted on a stud 72, carried by a spring controlled manually operated lever 73 fast on a rod 74 loosely mounted in the printer plate 67. The receipt strip 53, passing between the feed roller 65 and the tension roller 71, will 90 be fed toward the front of the machine a distance equal to the line spacing of the printing at each operation of a key 30.

To secure a visible impression a suitable continuous inking ribbon 59 is wound around guide rollers 60 mounted in the printer frame and over an inking roller 61 mounted upon a stud 62 projecting from the printer plate. This ribbon is held taut by a tension roller 63 supported in a frame pivoted upon a rod 64, supported in the printer frame. The ribbon is fed at each operation of a recording key 30 by means of a link 75 connected to the arm 69 and to the ribbon feeding lever 76 which carries a spring actuated 110 pawl (not shown) for conveying rotary motion to the ink roller 61.

The total printing mechanism in general is that described in detail in the application of Edward J. Von Pein, Serial No. 293,141, 115 and forms no part of this invention. It will be briefly described here.

The total printing wheels 48 are twice the diameter of the item printing wheels 52, and contain two sets of type characters, one set 120

for printing upon the receipt strip and the other for printing upon the total record strip 121, a sample of which is shown in Fig. 8. The complete mechanism for printing the total record strip 121, which contains a total of the records accumulated in the totalizer, is shown in the Von Pein application Serial No. 293,141 referred to.

The setting of the total printing wheels 48 (Fig. 6) is the same as that described in the Von Pein application and patent referred to, and only a brief description will be given here in connection with the electric motor operating device.

Upon operation of the electric motor or the crank handle which actuates the machine in total printing operations, the frame 102 is moved in a clockwise direction and carries with it a frame 229 mounted on a stub shaft 233 and connected thereto by a link 230. This movement permits the springs 220 to move the segment levers 221 in a clockwise direction and through partial gears 222 rotatably mounted on a shaft 223 and meshing with segments 225 on telescopic sleeves 47 carrying yokes 46, move said yokes in a counter clockwise direction, as viewed in Figs. 1 and 3, into engagement with the scrolls 45.

Referring to Fig. 5, the partial gears 222 carry segments 226 which mesh with gears 227 fastened to the left hand ends of telescopic sleeves 228 which on their right hand ends carry total printing wheels 48 (Fig. 6).

As the yoke members 46 (Fig. 1) swing into contact with the stepped scrolls, the total printing wheels are rotated to positions corresponding to the total of the items accumulated in the totalizer.

At the proper time, and by the operation of the totalizing mechanism, a platen bearing member 130 will be raised, bringing a platen 131 into contact with the type wheels 48. The platen bearing member 130 (Fig. 6) is pivotally mounted upon an arm 132, pivoted upon the stud 133 which projects from the printer plate 67. Simultaneously with the making of an impression upon the receipt strip, an impression will also be made upon the total strip 121 by mechanism not shown here.

The mechanism for giving an additional or greater movement to the feed roller 65, when printing totals, to feed the receipt strip a distance sufficient to bring the total past the severing means, is the same as that of the Von Pein applications referred to, and is briefly as follows: Fast upon the shaft 89 (Fig. 5) are two cams 100 and 101 which impart an oscillatory motion to a member 102 by contact with anti-friction rollers 103 and 104 carried on studs mounted in the member 102 which in turn is pivoted upon a shaft 105. Carried by the lower end of the oscillatory member 102 is an anti-fric-

tion roller 106 cooperating with a slot 107 in the segment arm 108, pivoted upon a stud 109 mounted in the machine frame 34 and meshing with a pinion 110 fast to an arm 111 pivoted upon the shaft 66 and having a slip pawl and ratchet driving connection with the feed roller 65. The oscillatory motion of the arm will rotate the feed roller 65, previously described.

The mechanism for resetting the totalizer to zero at the time of printing the total is identical with that described fully in the Von Pein applications, referred to, and will be but briefly described here.

The oscillating member 102 (Fig. 5), which is actuated by the operation of the electric motor, is connected by said link 230 and a second link 231 (Figs. 5 and 19) to a segment lever 232 pivoted on a shaft 233 and meshing with a partial gear 234 which is pinned to the shaft 223. A segment 235, which is also pinned to the shaft 223, meshes with a gear 236 attached to a disc 237 and freely mounted on a shaft 238. The disc 237 carries a spring controlled pawl 239 cooperating with a ratchet wheel 240 which is fast to a gear 241 (Fig. 3) meshing with a pinion 242 (Fig. 5) fast to a shaft 246 which is coupled with the totalizer resetting shaft 247 (Figs. 1, 2 and 3).

So far, the construction is substantially that of the Von Pein applications referred to.

For the purpose of carrying out the objects of this invention with the mechanism hereinbefore described, an electric motor is operatively associated with the total printing mechanism and means is provided for locking the item entering means and releasing the motor when it is desired to print a total of a transaction which means is actuated by the total printing mechanism to arrest the motor and to release the item entering means.

An electric motor 140 (Fig. 6), which primarily serves as an actuator in connection with the printing of totals on the receipt strip and also on the total record strip, is mounted on the right hand side of the machine frame and directly under the printer. The motor drives the printing mechanism through a clutch device, which is well known in the art and is shown in Figs. 15, 16, 17 and 18 for illustrative purposes only. Fast to the clutch shaft 141 (Figs. 6, 14 and 15) is a pinion 142 which meshes with an intermediate gear 143 freely mounted upon a stud 144 projecting from the side frame 34. The intermediate gear 143 also meshes with a gear 145 fast on the driving shaft 89. These gears make one complete revolution during each operation of the total printing mechanism.

The total printing mechanism is normally retained in an inoperative state by a swinging member 146 (Figs. 14 and 18) 130

which is freely mounted upon the driving shaft 89. This member 146 is formed at its lower end 147 to engage with various members of the driving clutch for opening and closing the circuit switch and stopping the total printer driving shaft.

The starting of the motor is manually controlled by a lever 148 (Figs. 9 and 14) freely mounted on a stud 149 projecting laterally from the side frame 34. Pivoted on a stud 150 mounted in the lever 148, is a downwardly extending member 151 guided near its lower end by a stud 152 mounted in the side frame of the machine and projecting through an opening 153 in member 151. A spring 154 attached to the pivot stud 149 and to a pin 155 projecting from the member 151, normally holds the lower side of the opening 153 in contact with the stud 152. The lower end of the member 151 has an angle edge 156 which contacts with a pin 157 projecting from the side frame of the machine, which, as the lever 148 is depressed, causes the member 151 to swing slightly in a clockwise direction. As a shoulder 158 on the member 151 moves past a flat sided pin 157 spring 154, will cause the member 151 to latch under the pin and retain the same in such position until near the end of the total printing operation.

Two spring controlled levers 159 and 160 (Figs. 5 and 14) are freely mounted upon a stud 161 projecting laterally from a horizontal bar 162, and are normally in contact with the flat side of the pin 157. On the forward end of the lever 159 is a formed ear 163 which overlaps the forward end 164 of the lever 160. An ear 165 formed on the member 151 will, when the motor starting lever 148 is depressed, contact with the ear 163 and cause both levers 159 and 160 to swing on their pivot 161, lowering the end 164 until it is below the flat side of the pin 157, when the bar 162 will move toward the rear of the machine under the tension of a spring 166. In this position the end 164 of the lever 160 will rest against the flat side of pin 157, and the formed ear 163 on lever 159 will be to the right of the formed ear 165 on the member 151. The horizontal bar 162 is supported upon two studs 167 and 168 which extend into slots 169 and 170 formed in the bar 162. The right hand end 175 of the bar 162 engages with a pin 176 projecting from the swinging member 146.

The downward movement of the motor starting lever 148 releases the lever 160 from the stud 157 which allows the bar 162 to move to the right (Fig. 14), swinging the member 146 a sufficient distance to disengage the end 147 from the motor driving clutch thereby closing the circuit and permitting the motor to operate the total printing mechanism as will be hereinafter described. As the intermediate gear 143 revolves in a clock-

wise direction, a cam 177, fast to the gear 143, will engage with a roller 178 carried by the lower end of the swinging member 146 and move the member forward to a position where the lower end 147 will engage with the various clutch members to break the circuit and stop the motor and also the total printing mechanism. As the member 146 swings forward the horizontal bar 162 moves with it, carrying the levers 159 and 160 forward. During this forward movement the ear 163 will contact with the right hand side of the ear 165 on the member 151 and swing the member on its pivot 150 thereby disengaging the shoulder 158 from the pin 157, to allow the motor starting key 148 to be returned to its normal position by the action of the spring 154. The forward movement of the bar 162 will also allow the end 164 of the lever 160 to assume its normal position to hold the bar 162 until the motor starting key is again pressed downward. The lever 160 will be returned to its normal position even if the starting key 148 is held in depressed position. It is therefore impossible to get repeat operations of the total printing mechanism by holding the starting key depressed.

The swinging member 146 (Fig. 18) normally retains a cam plate 180 against the tension of a spring 181, one end of which is attached to a pin 182 projecting from a disc 183, the other end being attached to a pin 184 projecting from the cam plate 180. As the cam plate 180 is released it moves in a clockwise direction to the extent of the length of a slot 185 in the cam plate through which the pin 182 passes to engage the end of the spring 181. This initial movement of the cam plate 180 (Figs. 10 and 11) closes the switch member 186 which causes the operation of the motor. Cooperating with the cam plate 180 is a roller 187 carried on a yoke 188 which is fulcrumed on a rod 189. The yoke 188 has an arm 190 cooperating with a roller 191 carried on a pivoted arm 192 which brings together the contact points of the switch member.

The cam plate 180 when released by the swinging member 146 changes its relation to the disc 183 so that the depressed part of the circumference on the cam plate is opposite the full diameter of the disc 183 which, as the plate and disc rotate in unison, will form a complete circumference of full diameter and retain the yoke member 188 (Figs. 10 and 11) in operated position until the cam plate is stopped by the return of the swinging member 146 to its normal position near the end of the total printing operation. A plate 193, fast to the cam plate 180, cooperates with the swinging member 146 to retain the cam plate in its normal position. Near the end of the operation a projection 194 on the swinging member 146 en-

gages a shoulder on the disc 183 which is fast to the pinion 142 and the motor clutch cam 195 and thereby stops the total printing mechanism after it has completed its operation. The projection 194 also engages a shoulder on a disc 196 which carries the rollers shown in Fig. 18 and thereby breaks the driving connection between the shell 197 and the clutch cam 195. As the motor and driving clutch are similar in construction to those shown in the Letters Patent to C. F. Kettering and W. A. Chryst, No. 1,144,418, granted June 29, 1915, only a brief description is here given.

To prevent a simultaneous manipulation of both the item entering keys and the motor starting key, a device is provided which will lock either element while the other is being manipulated. Fast on the shaft 78 (Fig. 14), which makes a complete revolution each time the item keys are operated, is a disc 200 having a notch 201 adapted to cooperate with a square pin 202 projecting laterally from a pitman 203. The rear end of the pitman is bifurcated and embraces the shaft 78 to be guided thereby as the starting key is operated. The forward end of the pitman is pivoted on a stud 204 mounted in an arm 205 extending downward from the motor starting key 148. As soon as the shaft 78 starts revolving, the slot in the disc moves out of alignment with the pin 202 thereby preventing an operation of the motor starting key. In the event that the motor starting key 148 is depressed before depressing any of the item entering keys 30, the pin 202 will enter the slot 201 in the disc 200 and thereby prevent rotation of the shaft 78, which, through mechanism previously described, will lock the item keys against manipulation.

In addition to the electric motor for operating the total printing mechanism, a manually operated crank 208 is provided, which will be but briefly described here as it is fully described in the Von Pein applications referred to. The crank 208 is freely mounted on a stud 209 projecting from the printer plate 67, this crank is connected by means not shown herein to one end of a sleeve 210, the other end of which carries a pinion 211 meshing with a gear 212 fast on the driving shaft 89 (Figs. 9 and 12). The operating crank 208 connects with the sleeve 210 through a clutch 213, and there is sufficient space between a countersunk shoulder on the crank (not shown) and the head on the stud 209 to allow the crank to be moved laterally out of engagement with the clutch member to allow the electric motor to operate the mechanism without rotating the crank 208. Referring to Fig. 12, the crank is shown clutched with the sleeve 210.

A roll 216 on an arm 217 pivoted on a stud 133 is drawn into engagement with a

cam 218 fast on the driving shaft 89 by means of a spring 215. The cam and spring cooperate to equalize the work of the total printing crank to permit of a nearly uniform rotation being given to the driving shaft 89. All of which is fully described in the Von Pein application Serial No. 376,088 referred to.

While the form of mechanism herein shown and described is admirably adapted to fulfill the objects primarily stated, it is to be understood that it is not intended to confine the invention to the one form of embodiment herein disclosed for it is susceptible of embodiment in various forms all coming within the scope of the claims which follow.

What is claimed is:

1. In a machine of the class described, in combination, a totalizer adapted to be restored to zero, means for entering items therein, separate means for restoring the totalizer to zero during an operation of said machine, and means for locking said item entering means and releasing said restoring means.

2. In a machine of the class described, in combination, a totalizer adapted to be restored to zero, means for entering items therein, separate means for restoring the totalizer to zero during an operation of said machine, and means operating to lock said item entering means and then to release said restoring means.

3. In a machine of the class described, in combination, a totalizer adapted to be restored to zero, means for entering items therein, separate means for restoring the totalizer to zero during an operation of said machine, means for normally locking the restoring means, means for locking the item entering means, and a connection between said locking means whereby the movement of either into locking position permits the other to be moved into unlocking position.

4. In a machine of the class described, in combination, a totalizer adapted to be restored to zero, means for entering items therein, separate means for restoring the totalizer to zero during an operation of said machine, means for normally locking the restoring means normally urged toward unlocking position, and means for locking the item entering means and for releasing the lock for the restoring means.

5. In a machine of the class described, in combination, a totalizer adapted to be restored to zero by an operation of said machine, means for entering items therein, separate means for restoring the totalizer to zero, means for locking the item entering means normally urged toward unlocking position, and means for locking the restoring means and releasing the lock for the item entering means.

6. In a machine of the class described, in combination, a totalizer adapted to be restored to zero by an operation of said machine, means for entering items therein, separate means for restoring the totalizer to zero, means for locking the item entering means and releasing the restoring means, and means automatically operating at the end of the restoring operation for locking 10 the restoring means and for releasing the item entering means.

7. In a machine of the class described, in combination, a totalizer adapted to be restored to zero by an operation of said machine, means for entering items therein, separate means for restoring the totalizer to zero, means for locking the item entering means during operation of the restoring means, and means automatically operated at 15 20 the end of the restoring operation for locking the restoring means and releasing the item entering means.

8. In a machine of the class described, in combination, a totalizer adapted to be restored to zero, means for entering items therein, means for restoring the totalizer to zero, locking means for the item entering means, locking means for the restoring means, and a common operating means for 25 30 moving said locking means for the item entering means into locking position and releasing said locking means for the restoring device.

9. In a machine of the class described, in combination, a totalizer adapted to be restored to zero, means for entering items therein, means for restoring the totalizer to zero, locking means for the item entering means, locking means for the restoring means, and devices on said locking means 35 40 for holding either locking means in locking position, either of said devices being adapted to render the other ineffective.

10. In a machine of the class described, in combination, a totalizer adapted to be restored to zero, means for entering items therein, means for restoring the totalizer to zero, means for locking said item entering means, means for locking said restoring means, shouldered means carried by a stationary part of the machine, devices on said 45 50 second mentioned locking means cooperating with said shouldered means to hold said second mentioned locking means in locking position.

11. In a machine of the class described, in combination, a totalizer adapted to be restored to zero, means for entering items therein, means for restoring the totalizer to zero, means for locking said item entering means, means for locking said restoring means shouldered means carried by a stationary part of the machine, devices on said second 60 65 mentioned locking means cooperating with said shouldered means to hold said second

mentioned locking means in locking position, and interengaging parts on said devices adapted to cooperate with each other to render either of said devices ineffective as the other is moved into operative position. 70

12. In a machine of the class described, in combination, a totalizer adapted to be restored to zero by an operation of said machine to take a total, means for entering items therein, separate means for restoring 75 the totalizer to zero, means for locking the item entering means, locking means for the restoring means, and connections between said locking means to effect release of either locking means as the other is moved into locking position, the parts being constructed so that the movement of either locking means into locking position must precede the release of the other locking means. 80

13. In a machine of the class described, in combination, a totalizer adapted to have a total printing position, total printing mechanism, means for holding the totalizer in such position, a lock lever for locking the total printing mechanism, and a connection 90 between said holding means and lock lever for releasing the lock lever after the holding means has become effective. 85

14. In a machine of the class described, in combination, a totalizer adapted to have a total printing position, total printing mechanism, means for holding the totalizer in such position, a lock lever for locking the total printing mechanism, a connection between 95 said holding means and lock lever to cause 100 either of these elements to move into unlocking position as the other is moved into locking position.

15. In a machine of the class described, in combination, a movable totalizer, item entering means involving mechanism for normally holding the totalizer in a total printing position, a total printing mechanism, means for locking said totalizer holding means in normal position, and means released by said 105 locking means for permitting operation of the printing mechanism. 110

16. In a machine of the class described, in combination, a totalizer, a plurality of keys for entering items therein, an item printing mechanism actuated by said keys, a total printing mechanism for printing the amount accumulated in the totalizer, means for locking the item entering means, means for locking the total printing mechanism 115 normally urged toward unlocking position, and a single manipulative means for moving the first mentioned locking means into locking position and for releasing the latter locking means. 120

17. In a machine of the class described, comprising a totalizer, item entering means and item printing means actuated thereby, total printing mechanism for printing the amount in the totalizer, power means oper- 125 130

atively connected to the total printing mechanism only, and common means for locking the item entering means and releasing the power means for operation.

- 5 18. In a machine of the class described, comprising in combination a totalizer, item entering means and item recording means actuated thereby, total recording mechanism for recording the amount in the totalizer, power means operatively connected to the total recording means only, manipulative means for releasing said power means, and locking means for said item entering means positively moved into locking position
- 10 15 by said manipulative means.

19. In a machine of the class described, the combination of a totalizer, totalizer actuating segments, a revolution cam shaft, item printing mechanism, item keys for actuating said segments, a total printing mechanism for printing the amount accumulated in the totalizer, releasable power means operatively connected to the total printing mechanism only, means for locking the item keys in their
- 20

normal position of rest, means for releasing the power means, and manipulative means for positively moving the item key locking means into locking position and for permitting operation of the power releasing means.

20. In a machine of the class described, in combination, a totalizer, item entering keys operable to actuate mechanism for entering items in the totalizer and for recording said items on an issuing strip, total printing mechanism for printing the amount accumulated in the totalizer on said issuing strip, power means operatively associated with the total printing mechanism, means for releasing said power means for operation, means for locking said item entering keys, and a manipulative key in alignment with and similarly actuatable to the item entering keys for rendering said locking means for the item entering keys and said power releasing means effective.
